AUTOMATIC CODE TRANSMITTING
TELEGRAPH SYSTEM

Harold J. Rosenberger, Rockville Centre, N. Y.,
assignor to All America Cables & Radio Inc.,
New York, N. Y., a corporation of New York

Application June 17, 1943, Serial No. 491,093

8 Claims. (Cl. 178—63)

This invention relates to automatic code transmitting telegraph systems and particularly to a system for transmitting Wheatstone code signals from cable code tape.

The Wheatstone code is a two element code employing the dot and dash signals of the standard international code, the signal elements being sent by positive or marking current, with the dashes three times the duration of the dots, while negative or space current is sent during the intervals between signal elements. The cable code is a three element code, employing positive current for dots, negative current of equal duration for dashes and no current for spaces or intervals. The cable code is customarily perforated on paper tape for automatic transmission by punching a series of center holes at uniform intervals, an additional hole above a center hole indicating a dot, an additional hole below a center hole indicating a dash, while a center hole alone indicates a space.

Under certain circumstances it is desirable to transmit automatically by Wheatstone code a message received and perforated on the tape in cable code, as in instances where a radio transmitter is associated with a cable receiver. The main purpose of this invention is to provide a system which may be automatically operated by cable code tape to send Wheatstone code signals. Other objects are to provide a simple, practical arrangement of this type employing standard types of equipment.

Additional purpose and advantages will appear from the following description considered in conjunction with the accompanying drawings, in which:

Fig. 1 is a diagram illustrating relationships between cable code tape and Wheatstone code signals; and

Fig. 2 is a diagram of a system embodying the invention.

Referring to Fig. 1, a section of cable code tape 10 is shown, punched with center holes 11, dot holes 12 and a dash hole 13, this arrangement of holes being suitable for transmitting the letter R. In carrying out the invention the tape is not uniformly fed. It is fed forward one center hole for each dot or space; but for a dash it is held stationary for a length of time corresponding to the duration of two dots or spaces, one feed step being omitted.

The time sequence of the feed of the center holes is indicated in Fig. 1 and designated "tape feed." Under it, in vertical register, the cycle of operations is indicated, this cycle consisting of a

series of feeding steps 14 synchronized with the center holes and a series of signal steps 15 intermediate to said holes. Means is provided for starting the transmission of a Wheatstone signal at each signal step 15 following a dot or dash hole. If a dot hole 12 is on the tape, the next feed step 14a includes the termination of the signal. If a dash hole is present, the subsequent feed step 14b is omitted and the signal transmission is maintained, continuing through the next signal step 15a and being cut off at the subsequent feed step 14a. The result is a dash signal 16 having three times the duration of a dot signal 12, and space signals 18 each equal to a dot signal, as indicated at the bottom of Figure 1.

Referring to Fig. 2, a suitable device for feeding the cable tape 10 is illustrated, various arrangements of this type being well known and adapted for use with the invention. The form diagrammatically indicated includes a feed cylinder 20 provided with feed pins 21 positioned to enter the center holes 11, and a ratchet 22 engaged by pawl 23 connected to armature 24 of feed relay 25, the arrangement being such that when relay 25 is energized the tape 10 will be fed one interval between center holes 11. Said holes are fed to an operating station in register with dot pecker 26 and dash pecker 27 of the usual type, each arranged to close a contact when the presence of a signal hole permits the registering pecker to pass through said hole. The details of this portion of the mechanism are standard and well known and therefore are not illustrated.

Means is provided for alternately connecting two circuit-energizing contacts to a source of potential, ordinarily positive, at synchronized intervals. While various electrical arrangements for accomplishing this purpose are known, a vibrating fork 30 is illustrated, said fork having a fixed period of vibration and being kept in motion by suitable means known in this art, indicated by contact 31 and magnet winding 32 connected to said contact and to a source of negative potential.

An arm of fork 30 is arranged to make contact alternately with sending circuit contact point 33 and feeding circuit contact point 34. Feeding point 34 is connected to armature 35 of polar relay 36 provided with two opposed windings, space winding 37 and mark winding 38. Armature 35 is normally positioned against space contact 39 and separated from mark contact 40. Since the contact 39 is connected through lead 55 41 to feed actuating relay 42 and thence to a

source of negative potential, the closing of contact 34 will normally energize relay 42. Armature 43, connected to a source of positive potential, will engage contact 44, connected to the winding of feed relay 25 and thence to a source of negative potential, feeding tape 10 one step.

In the absence of a signal hole in tape 10 in register with one of the peckers, the contact of fork 30 with sending point 33 will have no effect, and tape 10 will be fed one step for each cycle of the fork. When a dot hole 12 is fed beneath pecker 26 the next succeeding contact of fork 30 with point 33 will close a circuit extending from the fork through lead 47, pecker 26 and lead 48 to mark-winding 49 of polar relay 50 and thence to a source of negative potential. The armature 52 will be shifted into engagement with marking contact 53, connecting source 54 of marking or positive current to line 55.

The sending of a dot impulse will thus be started when fork 30 contacts point 33. Upon its next contact with point 34, however, the tape 10 will not only be fed in the usual manner, breaking the circuit through marking winding 49 of relay 50, but a circuit will also be completed through lead 57, spacing winding 58 of polar relay 59, lead 60, spacing winding 61 of polar relay 56 to a source of negative potential. This will shift armature 52 of relay 50 into contact with spacing point 64, ending the dot signal and putting spacing current from the source 65 on line 55.

When a dash hole 13 is fed into register with dash pecker 27, the next contact of fork 30 with point 33 will complete a circuit through said pecker, marking winding 67 of relay 50, marking winding 38 of relay 36 and resistance 68 to a source of negative potential. Armature 52 of relay 50 will be shifted into contact with point 53, starting a marking signal over line 55, and armature 35 of relay 36 will be shifted into engagement with contact point 40, breaking the feed and spacing circuits through point 39 and disabling the tape feed. Consequently, when fork 30 next contacts point 34 the tape will not be fed but an impulse will be sent through marking winding 69 of relay 59 connected to a source of negative potential, shifting the armature 70 into contact with marking point 71. Since armature 52 is not shifted the marking signal continues to be transmitted over the line. On the succeeding contact of fork 30 with point 33, however, a circuit is closed through lead 72, armature 70, point 71, spacing winding 37 of relay 36 and resistance 73 to a source of negative potential. Although marking winding 38 is still energized, resistance 68 is substantially higher than resistance 73, and consequently spacing winding 37 will overpower marking winding 38 of relay 36 and the armature 35 will be shifted to spacing position. On the succeeding contact of fork 30 with point 34, spacing winding 58 of relay 39 and spacing winding 61 of relay 50 will be energized, shifting the armatures of these relays to spacing position and placing a spacing or negative current on the line 55. The tape 10 is simultaneously fed in the manner already indicated, and the relays are in position to react to the next hole pattern on the tape.

It is apparent that an automatic system for sending Wheatstone code signals from cable tape has been provided by the addition of only three standard relays to the usual types of apparatus for feeding the tape, for providing properly timed contacts and for furnishing marking and spacing energy. While the preferred form has been disclosed, the invention is not limited to this ar-

rangement since various modifications may be made without departing from the invention. For instance, while polar relays have been disclosed and have special advantages including compactness and simplicity, substitute circuits employing non-polarized relays with suitable locking circuits may be used.

The references to cable code tape herein are intended to indicate the type of code tape in which a single hole at one side of the line of center holes is used to indicate a dot and a single hole at the other side is used to indicate a dash, said side holes constituting signal holes.

While a preferred embodiment of the invention has been illustrated, it will be apparent that the form shown may be substantially varied within the scope of the claims without departing from the invention.

What is claimed is:

20 1. An automatic telegraph transmitter for sending dot and dash signals from cable code tape comprising a code tape having signal holes including dash holes, step feed means for the tape to move it past an operative position where the signal holes are sensed and operated by impulse-controlled ratchet means, circuit means for operating said step feed means including relay means, circuit means including differential relay means for disabling said relay means whenever a dash hole is in operative position and sensed, signal-sending means including sending circuits, means including the disabling circuit means for closing a sending circuit whenever a signal hole is in operative position, and means for connecting at constant frequency alternately said relay means and said differential relay means to a source of energy.

40 2. An automatic telegraph transmitter for sending dot and dash signals from cable code tape comprising, a code tape having signal holes including dash holes, step feed means for the tape to move it past an operative position where the signal holes are sensed and operated by impulse-controlled ratchet means, circuit means for operating said step feed means including relay means, circuit means including differential relay means for disabling said relay means whenever a dash hole is in operative position and sensed, signal-sending means including sending circuits, further differential relay means for controlling said sending circuits and controlled in part by the disabling circuit means and including means for differentially operating different ones of said sending circuits when a signal hole is, and when it is not, in operative position and sensed, and means for connecting at constant frequency alternately said relay means and said differential relay means to a source of energy.

60 3. An automatic telegraph transmitter for sending dot and dash signals from cable code tape comprising, a code tape having signal holes including dash holes, and dot holes, step feed means for feeding the tape in steps arranged to position tape holes successively at an operating station where the holes are sensed, circuit means for operating said step feed means including relay means, circuit means for disabling said relay means whenever a dash hole is in operative position and sensed, signal-transmitting means, a unitary sending switch means for connecting said transmitting means alternately to a marking signal source whenever a signal hole is in operative position and sensed and to a spacing signal source whenever there is no signal hole in operative position, said sending switch means being controlled

by two sensing actuating switches in register with dot and dash holes respectively at said operating station, each arranged to close when in register with a hole, circuit means controlled by said sensing switches for locating said sending switch means in marking position when either one of said switches is closed, means controlled by said operating circuit means for opening said switches and locating said sending switch means in spacing position when a signal hole is shifted from the operating station, and means for connecting at constant frequency alternately said relay means and said disabling circuit means to a source of energy and effective to disable said step feed means when the dash hole switch is closed, for a period corresponding to one feed step, while maintaining said switch means in marking signal transmitting position until the next subsequent feed step.

4. An automatic telegraph transmitter for sending dot and dash signals from cable code tape comprising, a code tape having signal holes including dash and dot holes, step feed means for feeding the tape in steps arranged to position tape holes successively at an operating station where the holes are sensed, circuit means for operating said step feed means including relay means, signal-transmitting means, a sending switch arranged to connect said transmitting means alternately to a marking signal source and to a spacing signal source, a transmitting relay unit controlling said switch and controlled by two sensing actuating switches in register with dot and dash holes respectively at the operating station, each arranged to close when in register with a respective hole, circuits controlling said transmitting relay unit including a circuit connecting the dash actuating switch with said feed means and arranged to disable said feed means, and means for connecting at constant frequency alternately said relay means and said connecting circuit to a source of energy so as to disable said feed means for a period corresponding to one feed step and succeeding the locating and sensing of a dash hole at the operating station.

5. An automatic telegraph transmitter according to claim 4 in which said relay means comprises a feed connecting and disconnecting relay unit and a resetting relay unit therefor.

6. An automatic telegraph transmitter for

sending dot and dash signals from cable code tape comprising, a code tape having signal holes including dash holes, step feed means for the tape to move it past an operative position where the signal holes are sensed, circuit means for operating said step feed means, circuit means for disabling said step feed means whenever a dash hole is in operative position and sensed, signal sending means including sending circuits, means for closing a sending circuit whenever a signal hole is in operative position and sensed, and electro-mechanical vibrator means for connecting at synchronised intervals alternately said operating circuit means and said disabling circuit means, to a source of energy.

7. An automatic telegraph transmitter for sending dot and dash signals from cable code tape comprising, a code tape having signal holes including dash holes, step feed means for the tape to move it past an operative position where the signal holes are sensed, circuit means for operating said step feed means, circuit means for disabling said step feed means whenever a dash hole is in operative position and sensed, signal sending means including sending circuits, means for closing a sending circuit whenever a signal hole is in operative position and sensed, and an electromagnetically driven vibrating reed for connecting at synchronised intervals alternately, and at a predetermined frequency, said operating circuit means and said disabling circuit means, to a source of energy.

8. An automatic telegraph transmitter for sending dot and dash signals from cable code tape comprising, a code tape having signal holes including dash holes, step feed means for the tape to move it past an operative position where the signal holes are sensed, circuit means for operating said step feed means, circuit means for disabling said step feed means whenever a dash hole is in operative position and sensed, signal sending means including sending circuits, means for closing a sending circuit whenever a signal hole is in operative position and sensed, and a vibrating tuning fork unit electro-magnetically driven for alternately connecting at synchronised intervals, said operating circuit means and said disabling circuit means, to a source of energy.

HAROLD J. ROSENBERGER.
